DESIGN FOR A HANDBAG UNIT

Irving Pichel, New York, N. Y.

Application March 21, 1945, Serial No. 118,602

Term of patent 7 years

(Cl. D87—3)

To all whom it may concern:

Be it known that I, Irving Pichel, a citizen of the United States of America, residing in New York, county of New York, and State of New York, have invented a new, original, and ornamental Design for a Handbag Unit, of which the following is a specification, reference being had to the accompanying drawing, forming part thereof.

Fig. 1 is a front perspective view of a handbag unit showing my new design.

Fig. 2 is a rear perspective view thereof.

Fig. 3 is a front perspective view illustrating the individual portions.

I claim:

The ornamental design for a handbag unit, substantially as shown.

IRVING PICHEL.
